HANDLE FOR RESIDENCE LOCK OR THE LIKE

George P. Patriquin, Gardener, Mass., assignor to Independent Lock Company, Fitchburg, Mass., a corporation of Massachusetts

Filed Apr. 3, 1962, Ser. No. 69,562

Term of patent 14 years

(Cl. D10—8)

FIGURE 4 is an end view looking from the right of the handle for residence lock or the like;

I claim:

The ornamental design for a handle for residence lock or the like, substantially as shown.
